(57) **CLAIM**

The ornamental design for a projector screen with stand, as shown and described.

DESCRIPTION

FIG. 1 is a perspective view of a projector screen with stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view and taken from encircled portion labeled, “FIG. 9,” in FIG. 1;

FIG. 10 is an enlarged view taken from encircled portion labeled, “FIG. 10,” in FIG. 2;

FIG. 11 is an enlarged view taken from encircled portion labeled, “FIG. 11,” in FIG. 1;

FIG. 12 is an enlarged view taken from encircled portion labeled, “FIG. 12,” in FIG. 2;

FIG. 13 is an enlarged view taken from encircled portion enlarged view taken from encircled portion labeled, “FIG. 13,” in FIG. 2;

FIG. 14 is an enlarged view taken from encircled portion labeled, “FIG. 14,” in FIG. 5;

FIG. 15 is an enlarged view taken from encircled portion labeled, “FIG. 15,” in FIG. 6; and,

FIG. 16 is an enlarged view taken from encircled portion labeled, “FIG. 16,” in FIG. 6.

The dashed-dot lines form the boundary of the enlarged portion view of FIGS. 9-16 in FIGS. 1-2, 5-6 and 9-16 and

(Continued)

form no part of the claimed design. The even dashed broken lines shown in the drawings are included for the purpose of illustrating portions of the projector screen with stand that form no part of the claimed design.
